UNITED STATES PATENT OFFICE.

BENJAMIN KENOYER, OF EDINA, MISSOURI.

IMPROVEMENT IN GRINDING-MILLS.

Specification forming part of Letters Patent No. 39,735, dated September 1, 1863.

To all whom it may concern:

Be it known that I, BENJAMIN KENOYER, of Edina, in the county of Knox and State of Missouri, have invented a new and Improved Grinding-Mill; and I do hereby declare that the following is a full, clear, and exact description of the same, reference being had to the accompanying drawings, making a part of this specification, in which—

Figure 1 is a vertical central section of my invention, taken in the line $x x$, Fig. 2; Fig. 2, a plan or top view of the same.

Similar letters of reference indicate corresponding parts in the two figures.

This invention consists in providing the stones with drivers, arranged or applied in such a manner as to admit of the stones being adjusted at any time when required to keep them at right angles with their spindles.

To enable those skilled in the art to fully understand and construct my invention, I will proceed to describe it.

A represents a frame, which may be constructed in any proper manner to support the working parts of the machine; and B is a horizontal driving-shaft, which is placed in said framing, and has a bevel-toothed wheel, C, on its inner end. This wheel C gears into two similar wheels, D D', one of which, D, is at the upper part of the wheel C and the other, D', at its lower part, as shown clearly in Fig. 1. The lower wheel, B', is placed on the lower part of a spindle, E, the lower end of which is stepped in a block, F, said block being fitted in a box, G, which is secured to a cross-bar, a, in the lower part of the frame A. Through the box G set-screws b pass horizontally and bear against the sides of the block F, which is somewhat smaller in diameter than the interior of the box G, in order to admit of the lower part of the spindle E being adjusted laterally. The upper end of the spindle E is fitted in a similar block, H, which is placed in a box, I, on the top of the frame A, said box I having set-screws c passing horizontally through it, and which bear against the block H. By this means the upper part of the spindle E is rendered capable of being adjusted laterally. Four set-screws may pass through each box G I, the latter, as well as the blocks F H, being of square or polygonal form. The upper block and box are represented of polygonal form in Fig. 2.

J represents a tubular spindle, through which the spindle E passes loosely, so that both spindles may rotate independently of each other. The upper wheel, D, is fitted on the tubular spindle J, and the lower end of the latter rests upon friction-rollers d, which are fitted in a bridge-tree, K, in the frame A, and arranged so as to be capable of being adjusted by a screw, L, as usual. The tubular spindle J passes through two blocks, M M, which are fitted in boxes N N, secured on cross-bars e e in the frame A, and having set-screws f passing through them, to admit of the lateral adjustment of the tubular spindle. (See Fig. 1.)

O represents the upper stone, which rests upon the arms g of a driver, P. This driver has three arms, g, and it rests upon a shoulder, h, on the spindle E, the portion of the latter which passes through the driver being square, and having a screw-thread cut upon it to receive a nut, i, which is screwed down upon the driver and holds the same firmly on the spindle E.

Between the arms g of the driver P and the under surface of the stone O there are interposed strips j of india-rubber, and vertically through said stone, the rubber j and the arms g, screws k pass, one through each arm. These screws k perform two functions, to wit, they secure the driver firmly to the stone O, and they admit of the latter being adjusted at any time when necessary, so as to bring said stone at right angles with its spindle E, the stops j of india-rubber admitting of the stone being thus moved or adjusted under the action of the screws k.

Q is the lower stone, on which a driver, R, is fitted. This driver is provided with three arms, l, and is constructed precisely like the driver P of the stone O. The driver R has its arms l resting upon the upper surface of the stone Q, and screws m pass through these arms from the under side of the stone, strips of india-rubber n being interposed between the arms l and the stone. The driver R rests upon a shoulder o on the tubular spindle J, said driver being connected to said spindle in any proper way. The two stones O Q are encompassed by a curb, S, which may be arranged in any proper way, and provided with a discharge-spout, T.

From the above description it will be seen

that the two stones are rotated in opposite directions, and that either stone may be always kept at right angles with its spindles by adjusting the screws which pass through the arms of their drivers.

Having thus described my invention, what I claim as new, and desire to secure by Letters Patent, is—

Connecting the drivers P R to the stones

O Q by providing the former with arms *g i*, with india-rubber strips *j n* interposed between them and the stones, and having screws *k m* pass through the stones, rubber strips, and arms, substantially as herein described.

BENJAMIN KENOYER.
